UNITED STATES PATENT OFFICE.

ERNEST C. THORSCHMIDT, OF NEW YORK, N. Y.

DEVICE FOR HEADING AND HOOPING BARRELS.

No. 799,502.

Specification of Letters Patent.

Patented Sept. 12, 1905.

Application filed January 18, 1904. Serial No. 189,400.

To all whom it may concern:

Be it known that I, ERNEST C. THORSCHMIDT, a citizen of the United States, residing at the borough of Brooklyn, in the county 5 of Kings, city and State of New York, have invented an Improvement in Devices for Heading and Hooping Barrels, of which the following is a specification.

The staves of barrels are assembled and 10 the bilge-hoops applied in a machine especially constructed for making barrels to such extent.

My invention relates to devices for heading and applying the end hoop or hoops, 15 which operations are separate from the foregoing.

In carrying out my invention I employ a heading-up table and a catch-hoop for drawing together the ends of the staves for applying the end hoops. 20

The heading-up table comprises a flanged base, a tubular central column and clamping-ring, a removable threaded rod supported by said column, an exteriorly-threaded and 25 flanged sleeve, and platform connected to the flanged sleeve.

The catch-hoop comprises a bar, at one end of which is a circular disk and a hoop with eye ends pivoted to the same face of 30 the disk at places opposite to its center and on a line at right angles to the line of the bar. The platform is adjustable to bring the beveled end of the head into line with the croze of the staves, and the catch-hoop is then employed to bring the ends of the staves together and the edge of the head firmly into 35 the croze and to hold the same while the end hoops are being applied and secured to place.

In the drawings, Figure 1 is a vertical section and partial elevation of my improvement and a vertical section of the barrel in 40 position. Fig. 2 is a horizontal section and plan at the line $z-z$ of Fig. 1, showing the base and the central column and clamping-ring. Fig. 3 is a sectional plan at $y-y$ of Fig. 45 1 of the column, clamping-ring, and through the rod. Fig. 4 is an inverted plan of the sleeve and platform; and Fig. 5 is a plan of the catch-hoop device, showing its distended 50 position in full lines and its contracted position in dotted lines.

The base a , preferably of cast metal and circular in outline, is provided with a circular flange a' and a central split socket a'' on 55 the upper surface and with knobs or feet on the under surface at spaced-apart intervals

for supporting the same, there being a bolt 2 through flanges of the split socket for drawing the same together, so as to bind thereto the tubular central column b , which passes 60 down into the split socket. The upper end of the tubular central column b is split, and surrounding the same is a clamping-ring b' , having a tap-bolt 3 for securing the clamping-ring in position at the upper end of the 65 column b .

c represents a rod adapted at its lower end to pass into the upper end of the tubular central column b and removable therefrom and provided at its upper end with a threaded 70 portion, the central portion being of larger diameter than the lower end, so as to rest upon the upper end of the tubular column b .

I provide a sleeve d , having a flange d' . The sleeve is interiorly threaded at its upper 75 end to receive the threaded portion of the rod c , its lower end being of slightly greater interior diameter to pass over the central portion of the rod c . A platform e of circular outline is secured by screws to the flange 80 of the sleeve d , the said platform in diameter being slightly smaller than the diameter of the barrel-head.

f represents the staves of the barrel, and 4 the bilge-hoops, it being understood that 85 these staves are assembled and the bilge-hoops applied in a machine especially constructed for that purpose, but is independent of the device of my present invention, the said barrel so formed being headed by the 90 present device and the end hoops applied to hold the head in position.

g represents the parts forming the head of the barrel as resting upon the platform e , and 7 the croze of the staves into which the edge 95 of the head fits and is held by the end hoops i and k .

The catch-hoop structure comprises a bar h , on one end of which is a circular disk h' . The hoop m of the catch-hoop device is provided with eye ends and pivots 5, connecting these eye ends to the same face of the disk h' at places opposite to its center and on a line with the center, which is at right angles to the line of the bar h . Consequently when the bar 100 h occupies a vertical position the parts of the hoop m are in a plane, and the pivots 5, connecting the eye ends of said hoop with the disk, are also in the same plane, said plane being at right angles to the plane of the bar 105 h . This is the position of the parts when the catch-hoop device is applied around the

staves of the barrel to draw the ends thereof together and to close the same around the head of the barrel, bringing the beveled edge of the head into the croze of the staves. To 5 accomplish this, the bar *h* is turned from a vertical toward or into a horizontal position, as shown in Fig. 1. This swings the eye ends of the hoop *m* toward or into a vertical position, reducing the area of the hoop *m* and 10 forcing the staves together, and it will be apparent that the hoop may be still further narrowed or reduced in area by continuing the movement imparted to the bar *h* from a horizontal position downward into a more nearly 15 vertical position, because then the pivoted eye ends of the hoop pass by their vertical position and approach a horizontal plane in their extreme movement.

In the operation of this device the bar is to 20 be held in position by hand after the pressure has been applied and the ends of the staves brought together and the head *g* engaged by the croze of the staves, while the hoops *i* and *k* are driven to place and secured in the usual 25 manner to the staves. The reverse movement imparted to the bar *h* will of course relieve the pressure upon the hoop *m* and permit the same to expand and return to its initial position of greatest diameter, when the 30 same can be lifted off the head of the barrel ready to repeat the operation on another barrel and the barrel so headed be lifted off the device shown in Fig. 1, so that another barrel to be headed may take its place.

35 I claim as my invention—

1. In a device for heading and hooping barrels, the combination with a base and a platform, of a tubular central column, means for holding the same at its lower end to the 40 base, a rod threaded at its upper end and adapted to be received in the upper end of the column, and means for securing the same in position, a sleeve interiorly threaded and secured to the under surface of the platform 45 and adapted to engage the threaded upper end of said rod so as to adjust the height of the platform, and also fitting closely around the said rod beyond the threaded portion to be guided thereby and a device adapted to 50 surround the barrel and to which pressure may be applied for drawing together the staves at the upper end into contact with the

head, and the beveled edge of the head into the croze of the staves and for holding the same in position while the hoops are applied 55 and secured.

2. In a device for heading and hooping barrels, the combination with a base having a circular flange and a central split socket, and means for drawing together the parts of the split socket, of a tubular central column fitting in said socket and held thereby and split at its upper end, a clamping-ring surrounding the upper split end of the said column, a rod having a reduced lower end adapted to fit into the upper end of said tubular column and having its upper end threaded, a sleeve interiorly threaded and adapted to receive the threaded end of said rod and at its lower end to fit closely around and be guided 60 by the central portion of said rod, said sleeve being secured to the under surface of the platform and vertically adjustable for bringing the barrel-head to the desired height or position, and a device for drawing together the 65 barrel-staves at one end so as to force the same into contact with the head of the barrel and the beveled edge of the head into the croze of the staves and to hold the same in 70 position while the end hoops are being placed 75 and secured.

3. In a device for heading and hooping barrels, the combination with a base, a platform, means for adjustably supporting the platform upon the base and the base adapted 80 to receive a barrel to be headed, of a device for applying pressure and bringing together the ends of the staves, comprising a bar with a disk at one end, a metal hoop with ends pivotally connected to the same face of the 85 said disk at points opposite to its center and in a plane at right angles to the line of the handle, the disk being in a plane at right angles to the plane of the hoop, and to which 90 bar a swinging movement is imparted to 95 contract the area of the hoop and apply said pressure.

Signed by me this 14th day of January, 1904.

ERNEST C. THORSCHMIDT.
